UNITED STATES PATENT OFFICE.

WILLIAM A. BRECKON, OF LEE TOWNSHIP, ALLEGAN COUNTY, MICHIGAN.

PACKING DEVICE.

Application filed April 16, 1926. Serial No. 102,476.

The main objects of this invention are:

First, to provide an improved packing device for fruits, vegetables and the like by means of which the packing with a uniformly arranged top layer is greatly facilitated.

Second, to provide an improved packing device which greatly facilitates the packing or handling of the articles to be packed with little likelihood of injuring.

Objects pertaining to details and economies of construction and operation of my improvements will definitely appear from the detailed description to follow. The invention is clearly defined and pointed out in the claims.

A structure embodying the features of my invention is clearly illustrated in the accompanying drawing forming a part of my application, in which:

Fig. 1 is a perspective view of my improved packing apparatus with the parts in assembled relation.

Fig. 2 is a vertical section on a line corresponding to line 2-2 of Figs. 1 and 3, a layer of fruit being indicated as it is arranged in the initial step of packing, the retainer being shown in position preparatory to the next step.

Fig. 3 is a sectional view corresponding to that of Fig. 2 with the parts in position after removal from the diaphragm support permitting the fruit to assume a crowned position.

Fig. 4 is a detail plan view with the bottom removed.

Fig. 5 is a vertical section with the packer arranged in a basket, the basket being in upright position preparatory to withdrawing the packer.

Fig. 6 is a view corresponding to that of Fig. 5 after the packer walls have been withdrawn and prior to removing the bottom.

Fig. 7 is a perspective view of one of the side wall members.

Fig. 8 is a fragmentary plan view of the bottom.

Fig. 9 is a fragmentary section corresponding to that of Fig. 6 of a slightly modified form of bottom designed for a flat top pack.

My improved packing device comprises an annular frame 1 preferably formed of

angle iron and disposed with the angle 55 facing inwardly and downwardly, the horizontal arm of the frame providing an inwardly projecting ledge 2. The segmental side members 3 are hinged at 4 to this frame and are provided with inwardly projecting arms 5, 6 and 7, these arms all serving the same function but being of somewhat different shape and arrangement they are given different reference numerals for convenience in description.

The arms 5 are A-shaped while the arms 7 are arranged to overlap the arms 6, thus providing an open central space between these arms for a purpose to be pointed out later. Handles 8 are provided for convenience in 60 handling.

The inverted conical or concave bottom 9 is supported upon the frame above the inwardly projecting arms on the side wall members. A flexible diaphragm bottom 10 75 is secured at its outer edges to the bottom, this diaphragm being adapted to collapse within the bottom as shown in Fig. 3 or to be crowned upwardly as shown in Fig. 2.

The bottom has a central opening 11 to 80 receive the supporting post 12, the post being mounted on a disk base 13. This post engages a disk 14 secured to the diaphragm 10 so that when the parts are assembled as shown in Fig. 2 the diaphragm is supported 85 in an upwardly crowned position permitting the packing of fruit or other articles conventionally indicated at 15, beginning at the outer circle and filling in toward the center.

After one or more facing layers have been packed a retaining or follower disk 16 is arranged on the layer and the packer lifted from the support 12 allowing the diaphragm to collapse to the position shown in Fig. 3. 95 The packer is then filled with the articles to be packed, a basket 17 inverted over the packer, the parts brought to upright position as shown in Fig. 5 and the packer withdrawn. The open space between the inner ends of the arms permits the operator to place his foot upon the bottom holding it firmly upon the fruit so that the fruit is not disarranged. The yielding or pivotal mounting of the segmental side members 100 allows them to follow the outlines of the basket as they are withdrawn so that when 105

the packer is withdrawn the fruit maintains substantially its original position and is not bruised.

The diaphragm 10 is preferably provided with a padding 21 as is illustrated, this being of felt, wool or other suitable material, and yields so that the fruit is not bruised by pressure on the bottom. Further, with the bottom in the position shown in Fig. 6 10 the basket is "shaken down" to settle the fruit into position and this padded bottom effectively holds the facing layer, at the same time allowing the fruit to adjust itself during this shaking down operation.

15 In the packing of fruit for storage or the like it is desirable to secure what is known as a flat pack. A bottom such as is shown in Fig. 9 is then provided, the bottom 18 having a diaphragm 19 of limited crowning 20 movement. The disk 20 is preferably substantially larger than the disk 14.

I have illustrated and described my improvements in an embodiment which I have found very practical. I have not attempted 25 to illustrate or describe various modifications or adaptations as I believe the disclosure made will enable those skilled in the art to embody my improvements as may be desired.

30 Having thus described my invention what I claim as new and desire to secure by Letters Patent is:

1. In a basket packing device, the combination of an annular frame, a plurality of 35 segmental side wall members pivoted on said frame and provided with inwardly projecting arms disposed so as to provide a central open space between the inner ends of the arms, a concave bottom having a central 40 opening removably supported on said frame, a flexible diaphragm secured to said bottom adjacent the periphery thereof and having a central disk alined with the opening in said bottom, a support for holding said diaphragm in an upwardly crowned position 45 projecting through said opening in said bottom to engage said disk on said diaphragm, and a retaining plate for holding a layer of packed articles in position as the bottom is withdrawn from said support.

50 2. In a basket packing device, the combination of an annular frame, a plurality of segmental side wall members pivoted on said frame and provided with inwardly projecting arms, a concave bottom having a central 55 opening removably supported on said frame, a flexible diaphragm secured to said bottom adjacent the periphery thereof, and a support for holding said diaphragm in an upwardly crowned position projecting through said opening in said bottom.

60 3. A basket packing device comprising movably mounted side wall members, a removable concave bottom having a central opening, a flexible diaphragm secured at its

periphery to said bottom and having a central disk alined with the opening in said bottom, a support for holding said diaphragm in an upwardly crowned position disposed through said opening in said bottom to engage said disk on said diaphragm, and a retaining plate for holding a layer of packed articles in position as the diaphragm collapses upon the withdrawal of the bottom from said support.

70 4. A basket packing device comprising movably mounted side wall members, a removable concave bottom having a central opening, a flexible diaphragm secured at its periphery to said bottom and having a central disk alined with the opening in said bottom, and a support for holding said diaphragm in an upwardly crowned position disposed through said opening in said bottom to engage said disk on said diaphragm.

75 5. In a packing device, the combination of wall members adapted to receive a basket in inverted position, a concave bottom removably associated with said side wall members, a flexible diaphragm secured at its periphery 80 to said bottom, and means for temporarily supporting the center of said diaphragm in an elevated position permitting the collapsing thereof to crown a layer of packed articles, for the purpose specified.

85 6. In a packing device, the combination with an annular frame, of a plurality of segmental side members pivotally mounted on said frame and provided with inwardly projecting arms limiting the swinging thereof, 90 said arms being arranged to provide a central opening between their inner ends, and a removable bottom.

95 7. In a packing device, the combination with an annular frame, of a plurality of segmental side members pivotally mounted on said frame and provided with inwardly projecting arms limiting the swinging thereof, and a removable bottom.

100 8. In a packing device, the combination of an annular frame, a plurality of segmental side wall members pivotally mounted thereon and provided with supporting arms projecting inwardly below said frame, and a bottom loosely arranged on said frame above 105 said arms.

110 9. In a packing device, the combination of side members adapted to receive a basket in inverted position, and a concave bottom removably associated with said side members and provided with a diaphragm adapted to be supported in an upwardly crowned position or to collapse within the concave bottom.

115 10. A basket packing device comprising side wall members, a concave bottom removably associated with said side wall members and provided with a flexible diaphragm, means for supporting said diaphragm in an upwardly crowned position permitting it to be collapsed within the concave bottom, and 120

a retaining plate for holding packed articles in position as the diaphragm is collapsed.

11. In a packing device, the combination of a base, a plurality of side members pivotally mounted on said base, means for holding said side members in erected position to receive a basket permitting limited independent movement of said side members on

their pivots, and a bottom removably associated with said side members and constituting a follower for retaining the packed articles when the device is withdrawn from a basket arranged thereon. 10

In witness whereof I have hereunto set my hand.

WILLIAM A. BRECKON.
